UNITED STATES PATENT OFFICE.

WILLIAM J. BEISEL, OF BROOKLYN, NEW YORK.

NON-REFILLABLE BOTTLE.

Specification of Letters Patent. Patented Sept. 10, 1918.

1,278,294.

Application filed December 4, 1915. Serial No. 65,101.

To all whom it may concern:

Be it known that I, WILLIAM J. BEISEL, a citizen of the United States, and resident of Brooklyn, Kings county, State of New York, have invented certain new and useful Improvements in Non-Refillable Bottles, of which the following is a specification.

This invention relates to non-refillable bottles and in the drawing I have shown it applied to the type of bottle covered by my prior Patent No. 1,144,287, dated June 22, 1915, although it will be understood from the following description that it is also applicable to other non-refillable bottles of a different specific construction. The invention involves the use of two separated screens or sieves within the neck of the bottle between the outer guard and the valve. The purpose of the two screens is to prevent the possibility of floating a small particle around the guard through the neck of the bottle and lodging it between the valve and its seat. This would be very difficult to do in any case but it might be possible by the use of a small piece of cork fastened to the end of a hair. With the two perforated screens having the perforations out of line and the space between the screens being invisible from the outside it would be impossible for anyone to thus float an article into the neck of the bottle and lodge it beneath the valve. Heretofore it has been found practically impossible to make use of a perforated screen beneath the outer guard in a non-refillable bottle for the reason that it has been found that as ordinarily constructed the liquid will not flow through the screen so as to discharge the contents of the bottle when desired. The small perforations seem to prevent the entrance of air to take the place of the discharged liquid and thus the vacuum created by a slight discharge will prevent further flow. After my experiments I have discovered how the screen can be arranged so that it will permit a free flow of the liquid outward and I have further found that by my arrangement I can use two screens without interfering in any way with the free discharge of the liquid. The novel features of the invention will be apparent from the following description. In taken in connection with the drawing. In the drawing—

Figure 1 is a vertical section of a bottle embodying my invention.

Fig. 2 is a bottom plan view of the guard which is placed at the discharge end of the neck, and

Fig. 3 is a plan view of one of the perforated screens which I use.

As shown in the drawing, 1 indicates the body of the bottle which is provided with an integral neck portion 2. The outer section 3 of the neck is made separately and is placed above the portion 2 and secured thereto by the collar 4. Between the two sections of the neck there is clamped the valve seat 5 within which fits the tapered valve 6. When the bottle is in upright position the valve is held to its seat by the weight 7 which is flexibly connected to it. Above the valve seat 5 and resting on it is the cylindrical spacing member 8 and above the cylindrical member 8 there is a guard or protector 9 which is provided across its top with a disk 10 to prevent access to the parts on the inner side of the guard.

My invention relates particularly to the arrangement of the member 8 with reference to the guard 9 and the interposition between them of the two perforated screens 11, 12 separated by the opaque ring 13 which may be made of cork or other suitable material. The perforated screen 11 preferably has a projection on its under surface against which the valve 6 may strike when the bottle is inverted so that the valve will not close the perforations in the screen. I preferably make that projection by indenting the screen as shown at 14. It will further be observed that the passage through the guard member 9 is enlarged into a practically cylindrical extension immediately above the screen 12, thus providing an enlarged space above the screen. Within the guard and within the enlarged space I place lugs or projections 16 at intervals, their purpose being to prevent eddying of the liquid in that space and render it more quiescent. The two screens 11 and 12 are preferably separated some distance so as to allow considerable space between them. In practice it will be found that a distance of about a quarter of an inch will be satisfactory. The ring 13 being of opaque material it is impossible for anyone to see between the two screens.

I have found that it is practically impossible to make small bubbles of air pass through the perforated screen in the neck

- of a non-refillable bottle and have further discovered that in order to make the air pass freely through the screen and consequently to make the liquid discharge freely through it, it is necessary to provide means for making the small bubbles which naturally form come together in such condition that they will produce large bubbles of air against the outside of the screen. These 10 large bubbles will divide and pass through the perforations whereas the small bubbles would not. After passing through the perforations of the outer screen 12 the air is again in the shape of small bubbles and the space between the two screens is made sufficient to enable those small bubbles to collect and form large bubbles. It is for the purpose of this collection of the bubbles that the enlarged space 15 is provided above 20 the screen 12 and in order to assist in the formation of the large bubbles the projections 16 are provided retarding the circulation and eddying of the liquid. I have found that by this construction the liquid in the bottle may be discharged easily and regularly and that the air to take the place of the liquid will freely enter the bottle.
- Having thus described the invention, what is claimed and desired to be secured by Letters Patent is:
1. The combination with a bottle, of a guard within the mouth of the bottle having a tubular body extending inwardly, a perforated screen or sieve extending across the inner end of said tubular body, an enlarged free space being left on the outer side of said screen within said body for the collection of air bubbles, an opaque ring fitting against the inner side of said screen around its edge, a second screen or sieve fitting against the inner edge of said ring, the space between the two screens being sufficient to permit the collection of air bubbles, and automatic valve mechanism to prevent the ingress of liquid on the inner side of said second screen sufficient free space being

left on the inner side of said second screen for the collection of air bubbles.

2. The combination with a bottle, of a guard within the mouth of the bottle having a tubular body extending inwardly, a perforated screen or sieve extending across the inner end of said tubular body, an enlarged free space being left on the outer side of said screen within said body for the collection of air bubbles, projections on said body extending into said air space above said screen tending to prevent eddying of the liquid therein, an opaque ring fitting against the inner side of said screen around its edge, a second screen or sieve fitting against the inner edge of said ring, the space between the two screens being sufficient to permit the collection of air bubbles, and automatic valve mechanism to prevent the ingress of liquid on the inner side of said second screen sufficient free space being left on the inner side of said second screen for the collection of air bubbles.

3. The combination with a bottle, of a guard within the mouth of the bottle having a tubular body extending inwardly, a perforated screen or sieve extending across the inner end of said tubular body, an enlarged free space being left on the outer side of said screen within said body for the collection of air bubbles, an opaque ring fitting against the inner side of said screen around its edge, a second screen or sieve fitting against the inner edge of said ring, the space between the two screens being sufficient to permit the collection of air bubbles, and the second screen having an inwardly extending projection, a valve seat below said second screen and a movable valve for said seat adapted to rest against said projection on the second screen when the bottle is inverted, whereby the valve will not close the perforations in the screen.

In testimony whereof I affix my signature.

WILLIAM J. BEISEL.
